(57) **CLAIM**

The ornamental design for a binder spacer, as shown and described.

DESCRIPTION

FIG. 1 is a perspective front view of a binder spacer, in a folded position showing my new design;

FIG. 2 is a perspective back view in use on a binder in an expanded position thereof;

FIG. 3 is a top view (bottom view is same image) in use on a binder in a closed position thereof;

FIG. 4 is a front closed view thereof;

FIG. 5 is a back closed view thereof; and

FIG. 6 is a back side view (opposite side view is same image) in a closed position thereof;

FIG. 7 is a top view (bottom view is same image) in a closed position thereof;

FIG. 8 is an isometric front closed view thereof;

FIG. 9 is an isometric back view in a closed position thereof;

FIG. 10 is an isometric back view in a partially open position thereof; and,

FIG. 11 is an isometric back view in a fully open position thereof.

The broken line showing of elements in FIGS. 1, 2, and 3 is included for the purpose of showing environmental structure of the binder spacer and forms no part of the claimed design.
